FOLDER

John H. McLaren, New York, N. Y.

Application January 13, 1940, Serial No. 313,655

8 Claims. (Cl. 129—16.7)

This invention relates to folders of the type in which sheets of cardboard or pressed paper board or press board are connected by a flexible connector.

The sheets are usually connected by a fabric strip or strips with the longitudinal axis of the connecting strip parallel to the threads, warp or weft, of the fabric. When one of the sheets is pulled or twisted relative to the other the fabric rips.

This invention has for its salient object to provide a flexible connector of the character described that will have a longer wear than the usual connector and in which the liability to rip or tear has been reduced to a minimum.

Another object of the invention is to provide a flexible connector of the character specified that will cover the adjacent edges of both faces of the sheets and will overlap but will have a single thickness at the edges.

Another object of the invention is to provide adjacent connected edges of the sheets so constructed and arranged as to prevent abutting engagement with the edges of the connector.

Further objects of the invention will appear from the following specification taken in connection with the drawing which forms a part of this application, and in which

Fig. 1 is a perspective view of a folder constructed in accordance with the invention;

Fig. 2 is a plan view of the inside of a portion of the adjacent edges of the connected sheets and the connecting strip, before the strip has been folded around the bottoms of the edges of the sheets and secured thereto.

Fig. 3 is a view similar to Fig. 2 but showing the strip folded around the bottom and connected to the edges;

Figs. 4 and 5 are sectional elevations taken substantially on lines 4—4 and 5—5 of Fig. 2.

In the particular embodiment of the invention illustrated, there is shown a pair of sheets 10 and 11 of paper board which are connected by a flexible fabric connector 13. The connector may, if desired, have a V-shaped bend or bellows type fold therein.

The connector is formed of a strip 14 of fabric material, the strip being biased or, in other words, having the threads thereof disposed on a bias with respect to the inner edges of the sheets 10 and 11 and the longitudinal axis of the fold. The strip is secured preferably in the manner illustrated in Figs. 2 and 3 with the two ends disposed on the inside of the connector. One end 15 is secured at its edges to the inner surfaces of the

adjacent edges of the sheets 10 and 11 and the strip is carried around the upper edges of the sheets and downwardly along the outer surfaces, being secured thereto and extending below the lower edge, as shown in Fig. 2. The two ends 5 of the strip are preferably cut on an angle and the strip is of such a length that the outer edge shown at 16 will meet the outer edge shown at 17 when the downwardly extending portion of the strip is folded back and secured to the inner 10 adjacent faces of the sheets 10 and 11, as shown in Fig. 3. Moreover, the edge 18 meets the edge 19 in a similar manner. The portions of the strip between the edges 16 and 18 and 17 and 19 overlap, as shown at 20 in Fig. 3.

This particular arrangement is used since the meeting outer edges of the strip will have a single thickness instead of a double thickness, which would be the case if the ends of the strip overlapped for their entire width.

In order to prevent sheets of paper or other material carried in the folder from abutting against and engaging the outer edges 21 and 22 of the connecting strip, the inner edge portions of the sheets 10 and 11 are provided with projections or projecting portions 25 which extend outwardly from the outer faces and 26 which extend inwardly from the inner faces of the sheets. This construction is illustrated particularly in Figs. 4 and 5.

Since the strip is a bias material any tendency to tear or rip will be minimized, whereas with the ordinary strip connectors in which the strip is arranged with the warp or weft threads parallel with the axis or line of fold, the material is 35 easily ripped.

Although one specific embodiment of the invention has been particularly shown and described it will be understood that the invention is capable of modification and that changes in 40 the construction and in the arrangement of the various cooperating parts may be made without departing from the spirit and scope of the invention, as expressed in the following claims.

What I claim is:

1. In combination, a pair of sheets of relatively stiff material and a connecting strip of flexible woven material secured at its edges to adjacent edges of the sheets, said flexible strip being disposed with its threads bias to the connected edges of the sheets.

2. In combination, a pair of sheets of relatively stiff material and a connecting strip of double thickness, flexible woven material secured at its edges to adjacent edges of the sheets, said 55

flexible strip being disposed with its threads bias to the connected edges of the sheets.

3. In combination, a pair of sheets of relatively stiff material and a connecting strip of double thickness, flexible woven material secured at its edges to the inner and outer faces of adjacent edges of the sheets, said flexible strip being disposed with its threads bias to the connected edges of the sheets.

4. In combination, a pair of sheets of relatively stiff material and a connecting strip of flexible woven material secured at its edges to adjacent edges of the sheets, said flexible strip being disposed with its threads bias to the connected edges of the sheets.

5. In combination, a pair of sheets of relatively stiff material and a connecting strip of flexible woven material secured at its edges to the adjacent edges of the sheets on one face of the sheets and being folded around the ends of said edges and secured to the adjacent edges on the other face of the sheets.

6. In combination, a pair of sheets of relatively stiff material and a connecting strip of flexible woven material secured at its edges to adjacent edges of the sheets, said flexible strip being disposed with its threads bias to the connected edges of the sheets and being secured at its edges to the adjacent edges of the sheets on one face of the sheets and being folded around the ends of said edges and secured to the adjacent edges on the other face of the sheets.

7. In combination, a pair of sheets of relatively stiff material and a connecting strip of flexible woven material secured at its edges to adjacent edges of the sheets, said flexible strip being disposed with its threads bias to the connected edges of the sheets and being secured at its edges to the adjacent edges of the sheets on one face of the sheets and being folded around the ends of said edges and secured to the adjacent edges on the other face of the sheets, the ends of the strip overlapping at the central portion thereof but meeting at the edges of the strip.

8. In combination, a pair of sheets of relatively stiff material and a connecting strip of flexible woven material secured at its edges to adjacent edges of the sheets, said flexible strip being disposed with its threads bias to the connected edges of the sheets and being secured at its edges to the adjacent edges of the sheets on one face of the sheets and being folded around the ends of said edges and secured to the adjacent edges on the other face of the sheets, the ends of the strip overlapping at the central portion thereof but meeting at the edges of the strip.

5. In combination, a pair of sheets of relatively stiff material and a connecting strip of flexible woven material secured at its edges to adjacent edges of the sheets, said flexible strip being disposed with its threads bias to the connected edges of the sheets, and being secured at its edges to the adjacent edges of the sheets on one face of the sheets and being folded around the ends of said edges and secured to the adjacent edges on the other face of the sheets, the ends of the connector strip being single in thickness at the outer edges thereof and overlapping each other and being double in thickness at the overlapping portion inwardly of the outer edges.

6. In combination, a pair of sheets of relatively stiff material and a connecting strip of flexible material extending around the ends of adjacent edges of the sheets and secured at its edges to said adjacent edges on both faces thereof, the body of the sheets adjacent the edges of the connecting strip having raised portions projecting out of the planes of the sheets.

7. In combination, a pair of sheets of relatively stiff material and a connecting strip of flexible material extending around the ends of adjacent edges of the sheets and secured at its edges to said adjacent edges on both faces thereof, the body of the sheets adjacent the edges of the connecting strip having raised portions projecting out of the planes of the sheets, said flexible strip being disposed with its threads bias to the connected edges of the sheets.

JOHN H. McLAREN.
